HANGER FOR SUPPORTING CORRUGATED SHEETS

Filed Oct. 16, 1947

FIG. 2

FIG. 3

FIG. 4

FIG. 1

INVENTOR

ORVILLE A. HOWE

BY *Jerome A. Gross*

ATTORNEY

Patented Aug. 22, 1950

2,519,656

For curving and holding overlapping sheets of corrugated structural material, such as weatherboards, metal plates, and the like, to structural frameworks, such as roof and wall sheathing, and the like, the invention comprising a curved sheet-metal body portion 11, at the lower end of which are outward- and upward-extending lower flanges or fingers 12, and at the upper central portion of which is the outward-bent reinforcing tab 13. Through body portion 11 and tab 13 extends a tapped and threaded hole 14.

Corresponding to the position of said tapped and threaded hole 14, is slightly larger drilled hole 15 in the detachable upper hanger portion 16, which is curved to fit snugly against body portion 11 and like it is formed of sheet metal. Said detachable upper hanger portion 16 has at its lower end the inward- and downward-extending flanges or fingers 17.

Another object of my invention is to provide a thin hanger shaped to fit between the overlap of corrugated sheets, to slip over and grasp the upper edge of the overlapped sheet, and to support at a desired distance below said upper edge, and outside of said sheet, the lower edge of the overlapping sheet.

Another object of my invention is to construct such hanger in two detachable parts, so that after the overlapping sheet is secured to the framework, the parts of the hanger may be separated and the portion thereof extending between the corrugated sheets may be removed therefrom by motion in the direction of said corrugations, that is, perpendicular to the lines of overlap.

Another object of my invention is to provide simple means for attaching and detaching the two portions of said hanger.

Another object is to construct such a hanger simply but with adequate strength and rigidity to serve its functions.

With these and other objects in view, the invention consists in the construction and novel combination and arrangement of the parts hereinafter described, illustrated in the accompanying drawings, and set forth in the claims hereto appended, it being understood that various changes in the form, proportion and details of construction, within the scope of the claims, may be resorted to without departing from the essence of the invention or sacrificing any of the advantages thereof.

In the drawings:

Fig. 1 is an exploded perspective view of my invention.

Fig. 2 is a side elevation thereof as viewed from the innerside while in use as hereinafter described.

Fig. 3 is a sectional view taken along line 3—3 of Fig. 2.

Fig. 4 is a view partly in elevation and partly in section taken along line 4—4 of Fig. 2.

In its general organization, the preferred form of hanger shown in the drawings comprises a curved sheet-metal body portion 11 at the lower end of which are outward- and upward-extending lower flanges or fingers 12 and at the upper central portion of which is the outward-bent reinforcing tab 13. Through body portion 11 and tab 13 extends a tapped and threaded hole 14.

Corresponding to the position of said tapped and threaded hole 14, is slightly larger drilled hole 15 in the detachable upper hanger portion 16, which is curved to fit snugly against body portion 11 and like it is formed of sheet metal. Said detachable upper hanger portion 16 has at its lower end the inward- and downward-extending flanges or fingers 17.

A headed bolt 18 which may be the lead-headed type ordinarily used for affixing corrugated sheet roofing and siding material, equipped with a spacing nut 19, is inserted through the drilled hole

UNITED STATES PATENT OFFICE

HANGER FOR SUPPORTING CORRUGATED SHEETS

Orville A. Howe, South Affton, Mo.

Application October 16, 1947, Serial No. 780,202

2. Claims. (Cl. 108—33)

1. This invention relates to certain new and useful

improvements in hangers for applying overlapping sheets of corrugated structural material, and more particularly to such hangers for holding and spacing large sheets of corrugated material applied directly to structural frameworks, without intermediate sheathing, to serve as roofing or side walls of buildings.

It is assumed in the discussion which follows that the lines of overlap are substantially horizontal and that the corrugations are parallel to each other and run perpendicular to each horizontal line of overlap.

In applying large, heavy sheets of structural material as siding, considerable difficulty has been encountered in supporting the sheets while being spaced, drilled and affixed to the structural framework, particularly if attaching studs or brackets must also then be attached to the framework. To a lesser degree, the same difficulties are encountered in the use of such material for roofing on pitched roofs. It is now the general practice to hold such sheets in place during the application process by means of hoists or slings, which are removed at the final stage of attachment of the sheets. This practice is not satisfactory, however, not only because of the labor of attaching the hoists or slings to the sheets and supporting structure and subsequently detaching them, but more important, because of the difficulty in nesting the corrugations securely and in obtaining the exact overlap desired.

Flat overlapping structural members, such as weatherboards and metal plates, have sometimes been supported during their application by sliding or rolling hangers which could be moved horizontally along the length of the boards or plates as the work progressed, and thus be removed at the side of such members. For corrugated sheet material, this method was not feasible.

The principal object of my invention is to provide a removable device for holding large sheets of corrugated material while being applied to structural frameworks, and in so holding to cause the overlapping sheet to nest accurately in the corrugations of the overlapped sheet and to fix precisely the length of overlap.

Another object of my invention is to provide a thin hanger shaped to fit between the overlap of corrugated sheets, to slip over and grasp the upper edge of the overlapped sheet, and to support at a desired distance below said upper edge, and outside of said sheet, the lower edge of the overlapping sheet.

15 in detachable upper hanger portion 16 and engages the threads of hole 14, as shown in Fig. 4; whereby the body portion 11 and said detachable upper hanger portion 16 are held snugly together by the pressure of spacing nut 19.

In use, the hanger (so joined together by bolt 18) is placed upon the overlapped corrugated sheet 20 in the manner shown in Fig. 2, with the flanges or fingers 17 extending over and down on the inner side of the upper edge of said sheet, and the curved body portion 11 fitting into the corrugated outer surface of said sheet. The overlapping corrugated sheet 21 is then placed with its corrugations in alignment with those of the overlapped sheet 20, and set upon and within the outwardly extending flanges or fingers 12. It is obvious that the spacing nut 19 must be close enough to the tip of bolt 18 that this tip does not project far through hole 14, else it would interfere with the fit of the overlapping sheet 21.

With the hanger so holding the overlapping sheet, this sheet is secured to the structural framework; then bolt 18 is unscrewed from the inside of the wall or roof and detachable upper portion 16 removed from that side. The remainder of the hanger is removed from the outside by pressing downward on the flanges or fingers 12, causing the curved body portion 11 to move downward along the line of corrugation.

Thus far in the description I have referred to the detachable portion 16 as the upper portion, and described its flanges or fingers 17 as extending inward and downward; and have referred to the curved body portion 11 as fitting on the outer side of the overlapped sheet and as having outward and upward-extending flanges or fingers 12. This was done for purpose of clarity of description; but, as will be obvious if the drawing is turned upside down, the hanger itself may be turned upside down and used with the removable portion 16 on the outside and supporting an outer, overlapping sheet. This would be done should it be deemed convenient to remove bolt 18 from the outside of the work; in which case the curved body portion 11 would be removable from the inside by grasping flanges or fingers 12 and lifting upward.

It is also apparent without further illustration that it is inventively immaterial whether the hanger is constructed so that the body portion 11 is on the concave or convex surface of corrugation; similarly for the removable portion 16; similarly whether the flanges or fingers 12 and 17 are separate, as shown in the drawings, or continuous flanges. Other changes and modifications in both form and method of construction, arrangement and combination of the several parts of the bracket may be substituted for those herein

shown without departing from the nature and principle of the present invention.

Having thus described my invention, what I claim and desire to secure by Letters Patent is:

1. A hanger for supporting a sheet of structural material upon and overlapping another during erection, comprising a relatively thin body member having the same contour as said structural sheets and having greater length than the length of overlap, said body member having an outward- and upward-extending flange at the lower end thereof for supporting said overlapping sheet; further comprising a bracket member having as its lower portion an inward- and downward-extending flange, and having an upper portion adapted to fit against the inner side of said body member at a point above the overlap; and means inward of said overlapping sheet for removably attaching said upper portion of said bracket member against said inner side of said body member above the overlap.

2. A hanger for supporting a sheet of structural material upon and overlapping another during erection, comprising a relatively thin body member having the same contour as said structural sheets and having greater length than the length of overlap, said body member having outward and upward flanges or fingers at the lower end thereof for supporting said overlapping sheet, and having a tapped hole at the upper end thereof spaced from said lower end a greater distance than the length of overlap; a bracket member having an upper portion contoured to correspond with the contour of said body member, said bracket upper portion having a drilled hole larger than the said tapped hole in said body member, said bracket member further having at its lower extremity an inward and downward flanged portion adapted to grasp the overlapped sheet, and formed inward a distance at least equal to the thickness of said overlapped sheet; a bolt fitting through said drilled hole of said bracket member and engaging said tapped hole; and means on said bolt for pressing said bracket member against said body member.
